UNITED STATES PATENT OFFICE.

FRED A. DEXTER AND BAYARD P. DEXTER, OF ORANGE, MASSACHUSETTS, AND JAMES A. STUARD, OF HARRISBURG, PENNSYLVANIA; SAID BAYARD P. DEXTER AND SAID JAMES A. STUARD ASSIGNORS TO SAID FRED A. DEXTER.

MACHINE FOR FACING OR DRESSING GATE VALVES.

1,420,915.

Specification of Letters Patent. Patented June 27, 1922.

Application filed January 9, 1920. Serial No. 350,409.

To all whom it may concern:

Be it known that FRED A. DEXTER and BAYARD P. DEXTER, citizens of the United States, residing at and whose post-office address is Orange, in the county of Franklin, State of Massachusetts, and JAMES A. STUARD, a citizen of the United States, residing at and whose post-office address is Harrisburg, in the county of Dauphin, State 10 of Pennsylvania, have invented certain new and useful Improvements in Machines for Facing or Dressing Gate Valves; and they do hereby declare the following to be a full, clear, and exact description of the invention, 15 such as will enable others skilled in the art to which it appertains to make and use the same.

The invention relates to improvements in machines for facing or dressing gate valves 20 and has for its object to provide a simple and efficient machine of the character described that is capable of operating upon gate valves of various sizes and shapes to insure an accurate surfacing of the face of 25 the valve which engages the valve seat. To this end the invention comprises a table like base plate provided with two clamping jaws movable in opposite directions, longitudinally of the table, preferably by means of 30 an oppositely threaded screw shaft journalled below the table and engaging two travelling nuts, slideable in slots in the table top, said nuts having a pivotal connection with the corresponding clamping jaws, each 35 of which latter is provided with a pair of pivotal dogs, one mounted on each lateral face thereof, each dog having an adjusting screw mounted therein which regulates the elevation of the forward end of the corresponding dog so that the several dogs may 40 be adjusted to support the valve and bring the latter to a level to be engaged by the facing tool, when the valve has been engaged by the clamping jaws. In order to properly 45 adjust a wedge shape valve for engagement by the facing tool, the machine is provided with a transversely sliding block or wedge which is adjusted under the thin edge of the gate valve so as to bring the face of the 50 latter to a proper level. The machine also includes a vertically mounted tool engaging spindle capable of quick adjustment to accommodate valves and tools of varying thickness and also of a feeding adjustment by

means of which the tool may be advanced 55 toward the work to regulate the extent of the surfacing cut, said spindle being associated with a disc like cutter provided with adjustable cutter knives, so that when the lower end of the spindle engages a central 60 bearing in the back face of the cutter the cutting blades or knives rest upon the valve face and serve to trim or cut the metal of the valve face to the desired extent, as the cutter is intermittently rotated by means of 65 a handle and a friction band associated with the cutter disc.

In the accompanying drawings:

Fig. 1 is a front elevation of the machine showing the lower end of the tool spindle 70 ready to engage the rotary cutter.

Fig. 2 is a plan view of the machine with the standard and tool spindle removed.

Fig. 3 is an end elevation of the machine.

Fig. 4 is a plan view of the rotary cutter. 75

Referring to the drawings, 1 indicates a table or base plate, on the opposite ends of which are mounted standards 2, 2, supporting a cross piece 4, the several elements being secured together by suitable bolts. 80

Running longitudinally of the upper surface of the base plate is a rib 5 provided with two longitudinal slots 5', 5', which slotted rib constitutes a guide or track way for two clamping jaws 6, 6, which are adapted to 85 be moved toward and from each other for the purpose of engaging and clamping the lateral edges of a gate valve or similar element which is to be dressed or faced by the cutting tool. Concurrent movement of the 90 clamping jaws in opposite directions is effected by means of a shaft 9 journalled in bearings 11, 12 and 13 below the upper face of the base plate 1, said shaft being provided with oppositely disposed threaded sections, which engage nuts 7, 7, extending through the slots 5', 5', and connected respectively to the clamping jaws 6, 6 by means of pivot bolts 8, 8, extending through the clamping jaws and permitting an independent swiveling action of the respective jaws. The valve engaging faces of the 95 clamping jaws are formed as re-entrant angles which cooperate with the swiveling action of the respective jaws to accurately 100 center the valve, when the jaws are set up.

Pivoted at 16 to each forward lateral face of each of the clamping jaws 6 is a dog 15

having a screw 17 passing through the same, with its lower end in engagement with the top of the base plate to enable the outer end of the dog to be raised and lowered to engage 5 the under face or marginal edge of the valve so that by properly adjusting the four dogs 15 the valve may be accurately levelled, so that its face to be dressed or trimmed will be brought to a true horizontal plane. When 10 the valve, however, is of such shape as to be supported directly upon the base plate the dogs 15 may be swung backward on their pivots out of engaging relation.

When a wedge shape gate valve is to be faced by the machine, it is necessary to provide means for accurately supporting the thin edge of the valve and hold the valve in its accurately levelled position between the clamping jaws 6, 6. To effect this object 20 the base plate is provided with a transverse track way 20 provided with a longitudinal slot 21 to receive a sliding wedge member 23, tapering toward the center of the machine and having a dependent lug 24 which 25 engages and is guided in the slot 21. The upper face of the track way 20, and the lower face of the wedge 23 are provided with mating ratchet teeth 22, which serve to lock the wedge in its adjusted position thereby preventing a lateral canting movement of the 30 valve, after the same has been clamped by the jaws 6.

Mounted in a central hollow boss 30 in the cross piece 4 and in vertical axial alignment 35 with the center of the base plate 1, is a sleeve 31 having an integral collar 32 secured to the upper face of the boss 30 by studs 33 and locked to the under face of cross piece 4 by a set nut 34. The upper and 40 lower ends of the sleeve 31 are interiorly screw threaded for a short distance to provide a suitable engagement for the threaded tool spindle 41. The ends of the sleeve 31 are provided with longitudinal slots 35 and 38 respectively and are also provided 45 with tapered threaded sections 36 and 39, which are engaged by lock nuts 37 and 40 so that when the said lock nuts are set up on the threaded ends of the sleeve the interior threaded portions of the sleeve engage the corresponding screw threads on the tool spindle 41. When, however, 50 the lock nuts 37 and 40 are partially backed off the exterior taper ends of the sleeve, the slotted ends of the sleeve expand and release the tool spindle 41 so that the latter may be moved bodily longitudinally of the sleeve in a vertical direction, thereby 55 providing for a quick adjustment of the tool spindle with respect to the tool and the work. When the said nuts 37 and 40 are set up, however, the tool spindle can only be advanced or retracted by rotating the spindle by means of the hand wheel 42, as the 60 threads on the spindle are in engagement 65

with the interior threads of the sleeve aforesaid. This latter operation constitutes the feeding adjustment of the tool spindle.

The said tool spindle is provided in its lower end with a stud 43 engaging a socket 70 in the spindle end, and having a rounded boss 44 at its lower end adapted to engage a concave recess in the center of the back of the cutting tool.

An efficient form of cutting tool for use 75 of the machine as described is illustrated in Fig. 4 and comprises a disc member 50 having a central opening 51, which on the rear face is enlarged to form a concave socket to receive the hemispherical boss 44 on the 80 lower end of the tool spindle. Disposed around the outer edge of the disc 50 is a series of clamping studs 52, each adapted to receive a cutting blade 53, said blades being equilaterally triangular in cross section so 85 that any one of the edges may be presented to the work. These blades are each set at an angle to the radii of the disc 50 and may be adjusted longitudinally in the clamping members 52 to accommodate valves of varying 90 diameters. The cutting disc 50 is adapted to be superposed on the face of the valve to be surfaced or cut, in the position shown in Fig. 1, so that the cutting edge of each of the 95 tools 53 is in engagement with the valve face. The tool spindle is then turned down so that the boss 44 on the lower end thereof engages the recess 51 in the center of the cutter disc and rotary movement is imparted to the cutter disc by means of a friction band 54 100 which surrounds the peripheral edge of the cutter disc, said band being secured at one end to a block 55, in which is pivoted a lever 56, 57 to the lower end of which the other end of the band 54 is secured by a pin 105 58, the band being normally held taut, by means of a spring 59 interposed between the socket member 57 of the lever and abutment 60 secured in the block 55.

When the parts have been assembled, with 110 the valve in proper position, and the screw spindle brought into engagement with the cutter disc, rotary movement of the lever 56 in a clockwise direction tightens up the friction band 54 and imparts rotary movement to the cutter disc. Movement of the lever in an opposite direction releases the friction band 54 from its gripping engagement with the edge of the cutter disc and permits of the band being slid peripherally 115 around the disc without reversing the movement of the disc. Intermittent rotary movement of the lever and friction band 54 in opposite directions, therefore, provides an intermittent rotary movement of the cutter 120 disc in one direction so that a few turns of the disc will be effective in resurfacing the valve face, the extent of the cutting action being regulated by the feeding movement of the screw 41 under control of the operator. 125 130

It will be noted that the range of the movement of the clamping jaws 6 is large and, therefore, that the machine is capable of receiving and operating upon valves of various sizes, and as each machine is provided with cutter discs of varying size, it will be apparent that a single machine is adapted to operate upon gate valves of widely varying dimensions, and may be employed with equal facility with valves of the ordinary disc type or of the tapered or wedge type.

In operating upon valves of slightly different sizes it is necessary to adjust the cutters 53 longitudinally in their clamping supports, and to facilitate this operation one of the standards 2 is provided with a laterally projecting stud 63 upon which the cutter disc is adapted to be supported, by engaging the central opening 51 in the disc with the stud 63, thereby permitting the disc to be held in any desired position on the stud 63, by means of the lever 56, while the individual cutter members are properly adjusted.

What we claim is:

1. A facing machine for gate valves and the like, comprising a base plate, a pair of oppositely disposed clamping jaws having re-entrant work engaging faces slidably mounted thereon, a feed screw having oppositely disposed threads mounted on said base plate, nuts engaging the threaded sections of said feed screw, and a support having an inclined upper face mounted for sliding adjustment transversely of the base plate.

2. A facing machine for gates valves and the like, comprising a base plate, a pair of clamping jaws slidable longitudinally of the base plate, means for simultaneously moving the said jaws toward and from each other, including connections permitting a swiveling movement of the jaws, and a valve supporting wedge adjustable transversely of the base plate.

3. A facing machine for gate valves and the like, comprising a base plate, a pair of jaws slidable longitudinally of the base plate, a pair of work supporting dogs pivoted laterally of each jaw, means to adjust each dog with respect to the base plate, and means for simultaneously moving the jaws toward and from each other.

4. A facing machine for gate valves and

the like, comprising a base plate, a pair of jaws slidable longitudinally of the base plate, a pair of work supporting dogs pivoted laterally of each jaw, means to adjust each dog with respect to the base plate, and means for simultaneously moving the jaws toward and from each other, including connections permitting a swiveling movement of the jaws.

5. A facing machine for gate valves and the like, comprising a pair of clamping jaws slidable longitudinally of the base plate, means for simultaneously moving said jaws toward and from each other, valve supporting dogs pivoted on each side of the clamping jaws, means for adjusting the height of the ends of the dogs with respect to the base plate, and a support having an inclined upper face mounted for sliding adjustment transversely of the base plate.

6. A facing machine for gate valves and the like, comprising a base plate, a standard thereon, a vertical tool spindle mounted on said standard, a pair of clamping jaws slidably longitudinally of the base plate, means for simultaneously moving said jaws toward and from each other, a wedge support adjustable transversely of the base plate, and a facing tool engaging the lower end of the tool spindle.

7. A facing machine for gate valves and the like, comprising a base plate, a standard thereon, a vertical tool spindle mounted on said standard, a pair of clamping jaws slidable longitudinally of the base plate, means for simultaneously moving said jaws toward and from each other, valve supporting dogs pivoted laterally of each jaw, means for adjusting each dog with respect to the base plate, a wedge support adjustable transversely of the base plate, and a facing tool engaging the lower end of the tool spindle.
